CLAIM

The ornamental design for an adhesive tape, as shown and described.

DESCRIPTION

FIG. 1 is a top, front, right perspective view of an adhesive tape, showing our new design in an open configuration; FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The long and short broken lines in FIGS. 1-7 are included to show edges that form no part of the claimed design.
